CLAIM

The ornamental design for a boat, as shown and described.

DESCRIPTION

FIG. 1 is a left side elevational view of a boat showing our new design, the right side elevational view being a mirror image of that shown;

FIG. 2 is a top plan view thereof;

FIG. 3 is a front elevational view thereof;

FIG. 4 is a rear elevational view thereof;

FIG. 5 is a bottom plan view thereof, and

FIG. 6 is a top, front, left side perspective view thereof.
